UNITED STATES PATENT OFFICE.

JAMES TOTHAM, OF NEW HAVEN, CONNECTICUT.

DESIGN FOR A HOLDER FOR TOILET ARTICLES.

SPECIFICATION forming part of Design No. 23,416, dated July 3, 1894.

Application filed February 28, 1894. Serial No. 501,886. Term of patent 7 years.

To all whom it may concern:

Be it known that I, JAMES TOTHAM, a citizen of the United States, residing at New Haven, in the county of New Haven and State of Connecticut, have invented and produced a new and original Design for a Holder for Toilet Articles, of which the following is a specification, reference being had to the accompanying drawing, forming a part thereof.

5 The drawing is a perspective view of my design the leading features of which are the ornamental backing A from the outer surface of which project the semi-circular ornament

C, the rectangular tray B and the hook shaped extensions a—a and b—b in the relative positions and of the form shown in the drawing. 5

What I claim is—

The design for a holder for toilet articles, substantially as described and shown in the accompanying drawing. 20

JAMES TOTHAM.
